UNITED STATES PATENT OFFICE

JOHN E. PETERSON, OF IRVINGTON, NEW JERSEY, ASSIGNOR TO VAN VLAANDEREN MACHINE COMPANY, OF PATERSON, NEW JERSEY, A CORPORATION OF NEW JERSEY

TENTERING CLIP

Continuation of application Serial No. 495,871, filed November 15, 1930. This application filed August 27, 1931. Serial No. 559,713.

This invention relates to tentering clips for cloth tentering machines. The principal object of the invention is to provide a tentering clip whose movable jaw will not be permitted to close unless cloth is entered into the clip, it being known that the occurrence of closing without cloth being present in the clip (as on every idle or return run of the clip as a part of an endless chain comprising such clips, or 5 when for some reason the cloth fails to be entered on an active run, or whenever the machine is operated without cloth) produces considerable wear of the jaws requiring constant attention to insure good gripping condition. My invention accomplishes this result in a simple way, requiring in fact but the addition of a single part. Indeed, where according to the known practice the clip is to be prevented from gripping the cloth except 10 more or less near its very edge, it is possible by my invention that such part serve not only to prevent the closing movement of the movable jaw if cloth fails to be entered but to insure the grip being effected more or less near 15 the actual edge of the cloth.

In the drawings,

Fig. 1 shows the raceway of a tentering machine and a chain of one form of the improved clips in transverse section; 30 Fig. 2 is a plan of substantially what appears in Fig. 1;

Fig. 3 is a front elevation thereof;

Fig. 4 shows a clip of said form in front-to-rear vertical and nearly central section, the 35 solid lines showing the movable parts as they stand when the clip is open and the dotted lines showing them when the clip is nearly closed and the hereinafter described check shifted by the entered cloth from checking 40 relation to the movable jaw;

Fig. 5 shows said clip as in Fig. 4 and the check in checking relation to the movable jaw;

Figs. 6, 7 and 8 are fragmentary front-to-rear vertical and nearly central sections of the other form of the clip, Fig. 6 showing the movable jaw closed on the cloth; Fig. 7 said jaw held from contact with the fixed jaw by the check, and Fig. 8 the movable jaw open. 45

Let 1 represent the raceway on which a

chain of the clips travels, engaging a top forward or inner race 2 and an underneath or back race 3. The fixed jaw of each clip comprises a fork 4 and a plate 5 to which the fork is secured and which forms the part 55 of the clip that engages races 2 and 3, and such jaw may form with other such jaws the alternate or clip links in the chain whose connecting members are intermediate links 6. 7 is the movable jaw, which in this example is pivoted at 8 to the jaw carrier 9 in turn pivoted at 10 to the fork 4 of the fixed jaw and being a lever from which, when it engages a stop 11 against which it is normally urged by a spring 12, jaw 7 depends, so that the latter is then free, if cloth is entered between it and the plate 5, to coact with said plate to grip the cloth in response to any effort of the cloth to displace said jaw to the left in Fig. 1, for example, as when the clip and the companion clip of the opposite chain move apart to cause the tentering action. Jaw 7 is cleared from the cloth, when the cams (as α in Fig. 8) of the machine act on arm 9a of carrier 9 to shift the carrier 60 from stop 11, by contact of the abutment 9b with the jaw. I do not wish to be limited to the supporting of jaw 7 through any intermediary, such as 9. So much follows a 65 well-known construction. 70

Referring now to the form shown in Figs. 1 to 5: 13 is the mentioned check pivoted on a pin 14 of arms 7a of jaw 7 and movable in a plane cutting the grip-line of the jaws and having its left-hand or outer end the heavier and its other end a hook normally tending to catch on the fixed jaw, to wit, on a pin 15 thereof, due to the weight of its outer end. Whenever, the clip being open, jaw 7 descends with no cloth α entered between the outer end of the check and the fixed jaw (at 5), such descent is stopped by catching of the hook on pin 15. If however, cloth is present, when jaw 7 descends the check, first tilting as before, bears at its outer end on the cloth and in the continued descent of said jaw the check is then tilted in the reverse direction by the cloth, so that its hook clears pin 15 to allow the jaw to proceed toward actual cloth-gripping position (dotted lines, Fig. 100 95 105

4). If it is desired, as usual, that the clip be prevented from gripping the cloth except at its very edge the check is fashioned, as with the acute terminus 17, so that it 5 cannot enter a slot 16 in plate 5 and thus allow the jaw 7 to fall to grip the cloth until, as the clip recedes from the cloth, the latter stands well withdrawn from the clip, the 10 check thus acting as the well known controller to interrupt the closing movement of jaw 7 so that the grip of the jaws will take place more or less near the very edge of the cloth. When the jaw is next raised the hook of the 15 check, which was left under pin 15, engages said pin and the check is first tilted clockwise by the pin until its point clears the same, whereupon gravity tilts the check back to its normal position for catching on the pin on the ensuing down stroke of the jaw.

20 Figs. 6 to 8: Here the check, 18, is pivoted to the fixed jaw in a plane cutting the grip-line of the jaws and catches on the movable jaw. Said check has a slot 19 receiving the pin 15 and a slot 20 receiving pin 14 and 25 formed with a bent-off extension terminating in a seat 20a. Assume the clip is gripping the cloth (Fig. 6). On the next opening movement of jaw 7, as pin 14 approaches pin 15 the lower end of slot 19 will engage pin 15 to stop the incidental lifting of the check by the jaw and pin 14 now travels to the 30 bent-off extension of slot 20, allowing the check to fall by gravity so as to be positioned for pin 14 to catch on seat 20a on the next 35 descent of the jaw. On such next descent of the jaw, if no cloth is present, the upper end of slot 19 will come to rest on pin 15 and pin 14 will come to rest on the seat, so that jaw 7 is prevented from closing, as in Fig. 40. This check, as the one first described, thus normally (that is, always unless cloth is present) tends to obstruct closing movement of jaw 7. If cloth is present, the catching of pin 14 on the seat 20a does not occur because (Fig. 45 8, dotted outline of the check) the cloth stops descent of the check while pin 14 continues to swing downward with the jaw and so clears the seat. This check may also serve as a feeler or controller to interrupt closing movement 50 of jaw 7, to wit, by resting on the cloth over slot 16 to support jaw 7 against moving quite to the cloth-gripping position until, as the clip recedes from the cloth, the free end of the feeler clears the edge of the cloth and thus 55 allows the jaw to fall. A slot 19, rather than a plain hole receiving pin 15, is desirable as invariably resulting in the check releasing the movable jaw when the latter descends with cloth present because the check in such case 60 is capable not only of pivotal but of sliding movement on pin 15.

The essential feature of this invention, it will now be apparent, is a check (possible of being made to consist of but a single part, as 65 in both examples disclosed) normally posi-

tioned to obstruct movement of the movable jaw toward the other jaw but actuatable by the cloth to free the former for such movement thereof, in the examples on movement of said check with the movable jaw toward the other 70 jaw.

The movable jaw 7 preferably has its gripping portion 7x a blade formed separately, as of steel, and embedded in the jaw body in casting the latter, as by die-casting. The 75 blade 7x has one or more recesses 7y formed in it, and when the body of the jaw is cast the metal fills this recess so that the blade becomes permanently held in place. In previous constructions where the blade was embodied in the body it was held by rivets or the like, which in time worked loose leaving the blade loose and hence failing to grip the cloth accurately or with certainty.

This application is a continuation of my 85 application Serial No. 495,871.

Having thus fully described my invention what I claim is:

1. A tentering clip including a pair of jaws one of which is movable toward and from the other and when moved toward the other being adapted to grip cloth situated between them and a check normally positioned to obstruct movement of said movable jaw toward the other jaw but actuatable by the cloth to free the movable jaw for such movement thereof. 90

2. A tentering clip including a pair of jaws one of which is movable toward and from the other and when moved toward the other being adapted to grip cloth situated between them and a check movably connected to one jaw and normally positioned to engage the other jaw to thereby obstruct movement of said movable jaw toward the other jaw, 95 said check being actuatable by the cloth to free the movable jaw for such movement thereof. 100

3. A tentering clip including a pair of jaws one of which is movable toward and from the other and when moved toward the other being adapted to grip cloth situated between them and a check movably connected to one jaw and normally positioned to engage the other jaw to thereby obstruct movement of said movable jaw toward the other jaw, 110 said check being actuatable by the cloth on movement of said check with the movable jaw toward the other jaw, to free the movable jaw for such movement thereof. 115

4. A tentering clip including a pair of jaws one of which is movable toward and from the other and when moved toward the other being adapted to grip cloth situated between them and a check movably connected to the movable jaw and normally positioned to engage the other jaw to thereby obstruct movement of said movable jaw toward the other jaw, 120 said check being actuatable by the cloth to free the movable jaw for such movement thereof. 125

5. A tentering clip including a pair of jaws one of which is movable toward and from the other and when moved toward the other being adapted to grip cloth situated between them and a check movably connected to the fixed jaw and normally positioned to engage the other jaw to thereby obstruct movement of said movable jaw toward the other jaw, said check being actuatable by the cloth to free
10 the movable jaw for such movement thereof.
6. A tentering clip including a pair of jaws one of which is movable toward and from the other and when moved toward the other being adapted to grip cloth situated between them, and a feeler arranged to be interposed between the entered portion of the cloth and the movable jaw and adapted thereby to interrupt said movement of the movable jaw until on the retraction of the clip from the cloth the feeler clears the cloth, said feeler forming a check normally positioned to positively obstruct said movement of the movable jaw but actuatable by the cloth when entered
15 between the jaws to free the movable jaw for such movement.
